UNITED STATES PATENT OFFICE.

ANITA VON RADOSZEWSKI HANSEN, OF NEW YORK, N. Y.

BED-LINEN.

1,241,968.

Specification of Letters Patent.

Patented Oct. 2, 1917.

Application filed October 24, 1916. Serial No. 127,455.

To all whom it may concern:

Be it known that I, ANITA VON R. HANSEN, a citizen of the United States, and a resident of New York, in the county of New York and State of New York, have invented certain new and useful Improvements in Bed-Linen, of which the following is a specification.

My invention relates to bed clothing, and 10 one of the main objects thereof is to provide means whereby the blankets, comfortables, etc., may be maintained in a cleanly and sanitary condition by means of a readily laundried envelop supplanting the upper 15 sheet conventionally employed, and whereby said blankets, comfortable, and envelop, may be handled as a unit for airing and while making up the bed, and which envelop may also be used alone if desired, and may 20 be made very attractive to enhance the appearance of the bed.

A further object is to provide a readily removable sham for the bolster used during the day and which sham may also be used 25 with the pillows at night, an ornamental flap being preferably provided thereon for concealing the portions upon which the head of a sleeper had lain when the bed is made up, said sham being readily laundried 30 and contributing to the appearance of the bed.

My invention is fully described in the following specification, of which the accompanying drawings form a part, in which 35 like characters refer to like parts in each of the views, and in which:—

Figure 1 is an upper plan view of my envelop in use, partly broken away to show details;

40 Fig. 2 is an enlarged section taken on the line 2—2 of Fig. 1;

Fig. 3 is a similar section taken on the line 3—3 of Fig. 1;

45 Fig. 4 is a similar section taken on the line 4—4 of Fig. 1;

Fig. 5 is a view of my sham used with the bolster;

Fig. 6 is a view thereof inclosing pillows, ready for use for sleeping; and

50 Fig. 7 is a transverse section taken through the sham;

Referring to Figs. 1 to 4, inclusive, 8 represents the under solid portion of the envelop having side flaps 9 and 10 and end 55 flaps 11 and 12 joined thereto and constituting the upper portion of the envelop, the

flaps 9, 10 and 11 being preferably joined at their intersections whereas the flap 12 is free.

Within the envelop, at the sides thereof, 60 are strips 13 provided with spaced button holes, at the foot thereof is a strip 14 likewise provided with spaced button holes, and at the head thereof is a strip 15 likewise provided with spaced button holes, these strips 65 being blanket holders, and all of the flaps are also provided with spaced button holes and serve as a holder for a comfortable.

In assembling, the flap 12 is opened, as indicated by dotted lines in Fig. 1, and a 70 blanket 16 provided with buttons 17 is arranged beneath the side and foot flaps, the said buttons being inserted into the respective button holes in the oppositely arranged side strips 13, after which a blanket 18 is 75 similarly arranged within the envelop and buttons 19 thereon inserted into the respective button holes in the foot and head strips 14 and 15, respectively.

The more or less elaborate comfortable 80 20 is then similarly arranged within the envelop and buttons 21 thereon inserted into the respective holes in the flaps 9, 10, 11 and 12, and the blankets, comfortable, and envelop, constitute a unit for handling, the 85 solid under portion 8 being next to the sleeper and obviating the need for an upper sheet.

The sham 22 is cylindrical in form and open at one side, buttons 23 being provided 90 to close this opening, and said sham may be used upon the pillows while the bed is in use, or may be used upon the bolster during the time when the bed is not in use, an ornamental flap 24 being held along one edge to 95 the sham by the buttons 23 and being used to cover the soiled or rumpled portions of the sham when the bed is not being used and being thrown back out of the way, or detached, when the bed is in use.

100 The envelop and sham are intended to be marketed as a set, and the more or less elaborate ornamentation of one will be employed in the other, and it will thus be seen that the handling of but two units is necessary to manipulate two blankets, a comfortable, a sheet, and two pillows, in airing the bed clothing or in making the bed, and I may use duplicates of the strips for holding the blankets where more than two blankets 110 are desired.

My invention is very simple though en-

tirely practical and will appeal to house-keepers generally in view of the impossibility of soiling the blankets, thereby overcoming the present necessity for frequent 5 washing of said blankets, and this is also true with respect to the pillow cases.

While I have shown a simple ornamentation of the bed set, I do not limit myself to such ornamentation as I may make the 10 same as elaborate as may be desired by fastidious people or I may dispense with all ornamentation for people of simple tastes.

Having fully described my invention, what 15 I claim as new, and desire to secure by Letters Patent, is:—

1. A device of the class described, comprising an envelop having a solid under

side, flaps on its upper side at the edges thereof, the side flaps and one end flap being 20 joined together and the other end flap being free, strips within said envelop secured with one of their longitudinal edges at the edges of the envelop whereby they are free to accommodate a blanket below as well as above 25 the strip, and means for connecting said flaps and strips with bed coverings.

2. A device of the class described comprising, an envelop having flaps on its upper side at the edges thereof, strips within 30 said envelop secured with one of the longitudinal edges at the secured edges of the flaps, and means for connecting said flaps and both faces of said strips with bed coverings.

MRS. ANITA V. RADOSZIEWSKI HANSEN.
